UNITED STATES PATENT OFFICE.

SOLOMON S. BENSTER, OF TOLEDO, OHIO.

REPEATING ATTACHMENT FOR PHONOGRAHS.

1,368,384.

Specification of Letters Patent. Patented Feb. 15, 1921.

Application filed February 6, 1919. Serial No. 275,375.

To all whom it may concern:

Be it known that I, SOLOMON S. BENSTER, a citizen of the United States, residing at Toledo, in the county of Lucas and State of Ohio, have invented certain new and useful Improvements in Repeating Attachments for Phonographs, of which the following is a specification.

The present invention comprehends generally improvements in phonographs and more particularly relates to a repeating attachment for phonographs.

It is the primary aim and object of this invention to provide a device of the above mentioned character designed to be attached to the stand, rotating spindle and sound reproducer of a phonograph for acting in conjunction with a record on the rotating table to ultimately insure of the repeating of the record as many times as desired.

As an additional and equally important object this invention contemplates the provision of a device of the above mentioned character, wherein the component parts are of novel construction and are relatively adjustable with respect to the stand and with respect to each other so as to permit of the playing of various sized records, and also, to permit of the removal of the records when desired.

More particularly, the present invention consists in the provision of a device of the above mentioned character wherein a record contacting roller is adjustably mounted on the tone arm and is designed to contact with the record while coöperative stop means is associated with the roller shaft and the supporting arm on the stand so that the roller will act at predetermined times to swing the tone arm into a set position. Furthermore cam means are provided for incidentally acting in conjunction with the roller for raising the needle or stylus during the return movement of the tone arm.

The invention also embraces the provision of a device of the above mentioned character wherein the means for supporting and attaching the roller to the tone arm is of novel construction, the roller supporting frame being adjustable to vary the angular disposition of the roller with respect to the record grooves while the stop pins which are carried with the roller to coat with the sides

of the frame are relatively adjustable so as to be properly arranged with respect to the counter-balance weight on the axle to ultimately insure of the proper adjustment of these parts on any sized record in consequence returning or shifting the tone arm so that the needle or stylus will be properly engaged at the starting point of the record.

Among the other aims and objects of this invention may be recited the provision of a device of the above mentioned character with a view to compactness wherein the number of parts is comparatively few, the construction simple, the cost of production low and the efficiency high.

Other objects, as well as the nature, characteristic features and scope of this invention will be more readily apparent from the following description taken in connection with the accompanying drawings, and pointed out in the claims, forming a part of this specification.

The invention is clearly illustrated in the accompanying drawings, in which:—

Figure 1 is a top plan view showing the attachment applied on a phonograph, only a portion of which is shown,

Fig. 2 is a side elevation of the same,

Fig. 3 is an enlarged side elevational detail of the roller and the supporting frame,

Fig. 4 is a sectional detail of the same,

Fig. 5 is a fragmentary elevational detail of the means for mounting the supporting bar on the stand,

Fig. 6 is a fragmentary sectional detail of the means for supporting the opposite end of the supporting bar, and

Fig. 7 is a transverse sectional detail through the supporting bar showing one of the stops thereon.

Similar characters of reference are employed in all of the above described views, to indicate corresponding parts.

Referring now, more particularly, to the accompanying drawings there is illustrated a portion of a phonograph including a stand 1 having a top or platform 2 above which projects a vertically arranged rotating spindle for the revolving record carrying table 3 which is designed or adapted to support a record 4. A tone arm 5 is swingably arranged horizontally of the top or platform 6 and is fitted with a sound reproducer

which in turn carries a holder 7 for the needle or stylus 8 which operates on the record 4. Associated with the stand 1, the spindle and the tone arm, as well as the record, is 5 the improved repeating attachment which is designed to automatically return the tone arm immediately subsequent to the completion of the record so that the needle will be in a starting position for repeating the 10 record.

In reducing the present invention to practice there is provided an attaching bracket 9 which is secured to the side of the stand beneath the platform of the cover as by 15 fasteners 10, the upper portion being offset as at 11 while swingably connected for vertical movement to the upper end of the offset portion 11 of the bracket 9 is the inner end of a slightly longitudinally curved supporting bar 12, the pivotal connection being maintained by a pintle 13. A bracket arm 14 is connected to the outer terminal of the bar 12 and terminates in a cap or socket 15 which is designed to be fitted about the upper 20 end of the spindle while a screw 16 is mounted through the top of the cap or socket portion 15 for coacting with the upper end of the spindle and the bracket 9 in maintaining the bar 12 in desired spaced 25 relation above the record. As the cap 15 is removable from the spindle and as the bar is swingably connected for vertical movement, it is apparent that the same may be swung upwardly when it is desired to replace the record. Stop members 17 and 18 are formed with sleeved portions which are 30 slidably arranged on the bar 12 near the respective ends thereof as indicated for a purpose that will presently appear.

Coacting with the supporting bar 12 and the stops 17 and 18 thereof is the record engaging means designed for swinging the tone arm 5 so that the needle will be in a starting position immediately subsequent to 35 the completion of the record. In the present instance there is provided a bracket arm 19 the inner portion of which is curved arcuately to provide a stationary clamping jaw 20 to the outer end of which is pivoted 40 as at 21 a movable clamping jaw 22 also of an arcuate configuration while the clamping screw 23 is arranged through the outer end of the movable jaw 22 and adjustably engaged through the arm 19 and tightened sub- 45 sequent of course to arranging the jaws about the outer portion of the tone arm. An inverted U-shaped supporting frame 24 is now provided and is clamped to the under surface of the outer end of the arm 19 by 50 means of a suitable clamping element such as a screw 25, this arrangement permitting of the frame being positioned at various angles with respect to the arm 19 for a purpose that will presently appear. The frame 24 55 supports a roller 26 which is rotatably and

eccentrically mounted therein and designed to at times contact with the record for returning the tone arm so that the needle will be positioned at the starting point of the record.

In reducing the present construction to actual practice, the roller preferably consists of an annular body 27 having a grooved periphery to receive a rubber tire 28 for protecting the record against injury. The 70 annular body 27 is arranged about a concentric journaling portion 29 which projects from one face of a disk 30, the outer journaling portion being reduced as at 31 while the journaling portion and the disk are provided 80 with a bore 32 in which is frictionally engaged an axle 33 the outer end portions of which are journaled through bearings 34 at the lower ends of the frame 24. Another annular band 35 is frictionally engaged on 85 the reduced end 31 of the journaling portion 29 lying flush with the outer ends of the reduced portion so as to form a substantial disk. The engagement between this annular member or band 35 is frictional the same 90 as the engagement of the annular member 27 in the journaling portion 29, this arrangement permitting of the arranging of the pins 36 which project from the outer face of the disk 30 and the annular member or 95 disk 35 in various positions relative to each other. It is also to be understood that the shaft or axle 33 is capable of sliding through the bearings 34 to ultimately permit of the pin 36 coacting with the adjacent sides of 100 the frame 24. A counter-balance weight 38 is connected to one projecting portion of the shaft 33 exteriorly of the same and extends at right angles to the longitudinal axis 105 of the shaft and over the center of the roller 105 so as to be positioned as shown in Fig. 3, to hold the pin 36 against the adjacent side of the frame when the roller or wheel is arranged in close relation with the same side 110 of the frame, while in addition one of the principal purposes of this weight is to cause the roller to engage the disk immediately 115 subsequent to the shifting of the axle in a manner that will hereinafter become apparent and consequently return the tone arm 115 to a starting position. In this connection it is to be particularly understood that the disengagement of one or the other of the pins 36 is effected when the device comes in 120 contact with the stop members 17 or 18. In returning these parts to the position described or in other words setting the tone arm so that the record may be repeated a bracket arm 39 extends from the opposite side and has pivoted thereto a horizontally 125 swinging stop arm 40 for coacting with the stop 18, said stop arm 40 carrying a concaved disk 41 to act against the convex head 42 formed on the oppositely projecting extremity of the shaft 33. In this connection 130

it is to be particularly understood that subsequent to the release of the inner pin 36 from the adjacent side of the frame 24 which is effected by the contact of the weight 38

- 5 with the stop 17, the roller 26 owing to the peculiar positioning of the weight 38 moves downwardly and engages the record and inasmuch as the frame 24 is arranged at an angle to the disk the said roller will revolve 10 and carry the tone arm toward the outer edge of the record; when near the outer end or starting point of a record the stop arm 30 strikes the stop 18 so the disk 40 will in turn strike the head 42 and shift the shaft 15 releasing the opposite pin 36 from the adjacent side of the frame, the counter-weight on the shaft in the meantime assuming a position slightly over the center so that immediately subsequent to the disengagement of 20 the last mentioned pin 36 the weight will act to raise the roller from the record and will in turn be held against further downward movement by the reengagement of the pin 36 with the frame. The needle of course 25 engages the starting point of the record immediately subsequent to the raising of the roller from the record by the counterweight. It will thus be seen that the tone arm and needle are in position to repeat the record 30 and it is equally well apparent that owing to the particular arrangement of the repeating attachment or repeating mechanism that the parts will be automatically adjusted to again reset the mechanism as soon as the 35 counterweight strikes the stop 17.

It is believed in view of the foregoing description that a further detailed description of the operation of the invention is entirely unnecessary. Likewise, it is believed that 40 the advantages of the invention will be readily apparent. However, in this connection it is to be particularly understood that owing to the connection of the frame 24 with the arm 19 and the relatively adjustable pin 45 36 as well as the adjustable stops 17 and 18 that various sized records may be played and repeated for as many times as desired.

Still further embodiments of the invention than those herein especially defined may 50 be resorted to as conditions or preference may dictate, as may be in keeping with the hereto appended claims.

Having thus fully described the invention, what is claimed as new and desired to be 55 secured by Letters Patent, is:—

1. In a repeating attachment for phonographs, the combination with a tripping device, a support adapted to be mounted on the tone arm of a phonograph, an eccentrically mounted hub carried by the support, a roller on the said hub, and means associated with the hub for actuating the same upon engagement with the tripping device whereby to move the roller into contacting engagement with a record for re-

turning the tone arm to its starting point, and for raising the roller and lowering the needle subsequent to the return movement of the tone arm.

2. In a repeating attachment for phonographs, the combination with a tripping device, a support adapted to be mounted on the tone arm of a phonograph, an eccentrically mounted hub carried by the support, a roller on the said hub, means associated with the hub for actuating the same whereby to move the roller into contacting engagement with a record for returning the tone arm to its starting point, and for raising the roller and lowering the needle subsequent to the return movement of the tone arm, and means for regulating the operation of said actuating means associated with the tripping device.

3. In a phonograph, the combination with a rotating table having a record thereon, a horizontally swingable tone arm and a needle carried with the tone arm, of spaced stops, a bracket connected with the tone arm, a frame adjustably connected to and depending from the bracket, a shaft slidably and rotatably mounted in the frame, a roller carried eccentrically by the shaft, and coöperative means on the shaft, the roller and the frame for respectively coacting with the first mentioned stops in alternately moving the roller into contacting engagement with the record for swinging the tone arm and for raising the roller and lowering the needle subsequent to the return movement of the tone arm.

4. In a repeating attachment for phonographs, the combination with a tripping device, a support adapted to be mounted on the tone arm of a phonograph, a rotatable shaft mounted in the support and adapted for slight lateral movement with respect thereto upon contact with the tripping device, means for rotating the shaft, means on the shaft for engagement with the support upon lateral movement thereof for limiting the rotational movement of the shaft, an eccentrically mounted hub on the shaft and a roller on the hub adapted to be moved upon rotation of the shaft into contacting engagement with the surface of a record for returning the tone arm to its starting point and moved out of engagement with the record by rotation of the shaft for lowering the needle subsequent to the return of the tone arm.

5. In a repeating attachment for phonographs, the combination with a tripping device, a support adapted to be mounted on the tone arm of a phonograph, arms on the support, a rotatable shaft journaled in the arms of the support and adapted for slight lateral movement with respect thereto upon contact with the tripping device, a counter-balancing weight on the shaft for

rotating the same, disks on the shaft, pins on the disks for engagement with the arm of the support whereby to limit rotational movement of the shaft, an eccentrically mounted hub on the shaft, and a roller on the hub adapted to be moved into engagement with the surface of a record upon rotation of the shaft whereby to return the

tone arm to its starting point upon completion of a record, and out of engagement with the record by rotation of the shaft to lower the needle upon completion of the return movement of the tone arm.

In testimony whereof, I affix my signature hereto.

SOLOMON S. BENSTER.
